SHUTTLELESS LOOMS WITH CONTINUOUS WEFT FEEDING

Raymond Dewas, Amiens, France

Application February 18, 1952, Serial No. 272,049

Claims priority, application Great Britain
February 23, 1951

4 Claims. (Cl. 139—123)

This invention relates to improvements in shuttleless weaving looms with continuous weft feeding, and has reference to weft feeder looms without pirn, of the kind in which the weft is inserted either by a single weft feeder or needle, or two oppositely arranged weft feeders or needles, one of which conducts the weft to the middle of the shed where it is taken up and drawn by the other to the selvedge.

The invention has reference to the movement of the single picking arm, or of the two oppositely arranged picking arms, positively operating the needle or needles for the insertion of the shoot, the picking arm or each one of the picking arms being positively driven, for instance, by a cam provided with a helicoidal groove co-operating with a roller, the shaft of which is fixed to the lower end of the picking arm.

The great speeds now reached by this kind of loom impose important stress on the cam, the roller and its shaft, owing to the accelerations and decelerations that occur.

The principal object of the invention is to reduce the fatigue of these members to a considerable extent and modify the profile of the cam to increase the rapidity of the accelerations and decelerations, so that the extents of the idle periods are reduced, with the result that the cycle of operation is utilized more effectively, and the maximum instantaneous speed of the needles is reduced, thus bringing about, among other things, a reduction in weft breakages.

According to this invention, the positively operated picking arm is submitted to the action of one torsion bar or/and torsion tube, or of several of them, the torsion bar or tube being placed preferably in the centre of the shaft, hollowed to that effect, around which the picking arm oscillates. In that case, the bar is fixed at one of its ends to the end of the shaft, or to an extension of a part supporting said shaft or the oscillating picking arm, or still, mounted in an independent carrier, whilst the other end of said torsion bar is attached to the hub of the picking arm.

The picking arm can be submitted to the influence of the torsion bar only on certain portions of its stroke; for this purpose, one or the other of the ends of this bar and/or a co-operating of the picking arm or of its oscillation shaft can be fitted with any mechanical, hydraulic or other suitable device.

It will be realized that, during speed reduction, a large part of the kinetic energy of the picking arm and of the needle, energy which it is thought advisable to compensate for avoiding the fatigue and wear of the parts, is stored in the torsion bar, which restores it on the next acceleration to the picking arm, with the result of economy of motive force and possibility of increasing speed.

On stopping the loom, the torsion bar may be disconnected either automatically or by hand, to enable the loom to be turned conveniently by hand, and on starting the loom again, reengagement may be automatic.

It is to be understood that the principle described above

2

is applicable more particularly, either to a picking arm operating a needle by means of a small rod, or to a picking arm driving the needle by different means, or to a picking arm driving two oppositely arranged needles by a known articulation system, or to a picking arm of which the upper part consists of a toothed sector intended to set in action the pinion fixed on the shaft of a wheel which drives a band or ribbon to which the weft feeder or needle is fixed.

10 Other characteristics and advantages of the invention will also be found in the following description of one form of construction which is given simply by way of a non-limitative example and is diagrammatically shown in the attached drawings, in which:

15 Fig. 1 is a part sectional front elevation of the end of a batten of a loom with oppositely arranged weft inserters or needles showing a picking arm, the driving members therefor and its oscillating casing with its cover removed;

20 Fig. 2 is an end elevation of Fig. 1, the casing being sectioned on the line II—II of that figure and shown as occupying the forward position in its oscillating movement;

25 Fig. 3 is a plan view of the casing, showing the arrangement and the mounting of the torsion bar provided at the centre of the tubular shaft about which the picking arm oscillates;

30 Fig. 4 is an enlarged diametral sectional view on a vertical plane through the torsion bar of Fig. 3 showing details of the mounting of the torsion bar;

35 Fig. 5 is an end view showing the mounting of the rear end of the torsion bar;

Fig. 6 is a horizontal sectional view taken on the line VI—VI of Fig. 5;

40 Fig. 7 is a vertical sectional view, similar to Fig. 4, showing another embodiment of the mounting of the torsion bar;

Fig. 8 is a plan view, similar to Fig. 3, showing an embodiment comprising two cooperating torsion bars;

45 Fig. 9 is an elevational side view, showing a torsion bar of great length cooperating at its rear end with guiding means provided on a stationary carrier, independent with respect to the casing;

Fig. 10 is a sectional view taken on the line X—X of Fig. 9.

50 In the drawings, 1 is the batten having the channel 2 in which slides the weft inserter or needle, not shown, operated by the picking arm 3 by means of the connecting rod 4.

55 The batten 1 is attached to the swords 5 so that it can pivot about the axis of the lower shaft 6 supported by bearings 7 carried on the frame 8.

The casing 9 is rotatably mounted on the lower shaft 6 so that it can pivot freely thereon, the end plates 9a of the casing 9 forming bearings therefor. The casing 9 is arranged to partake of the oscillating movement of the batten 1 by a connection consisting, in the example shown, of a crosspiece 10 fixed at 11 to the sword 5 and at 12 to the flange 9b that projects upwardly from the casing 9.

60 Within the casing 9 is arranged the cam 13 that is keyed on the lower rotating shaft 6 and is provided with an endless helicoidal groove 14 that engages with a roller 15 the spindle 16 of which is mounted in the lower end of the picking arm 3. The extreme positions taken by this roller, in the movement imparted to it by the groove 14, are indicated in Fig. 1 at 15' and 15'', whilst the corresponding positions of the picking arm 3 are indicated by the chain lines 3' and 3'' in that figure.

65 The casing 9 consists of a body, the profile of which is clearly shown in Fig. 2, having a front opening which is closed by a cover 17.

The picking arm is oscillatingly mounted on the

upper part of the casing 9 from which it emerges at the location of the mounting.

According to the invention, the picking arm 3 is submitted to the action of one torsion bar or/and torsion tube, or of several of them.

In the embodiment shown in Figs. 1 to 6, the picking arm is oscillatingly mounted on a tubular shaft through which passes a torsion bar, the fore end of which is connected to the picking arm whilst its rear end is mounted between abutting members made integral with the casing. 10

The hub 3a of the picking arm 3 is mounted, through interposition of a bearing 18, on a tubular shaft 19 fitted by means of nut and counter-nut 20. The torsion bar 21 passing through the tubular shaft 19 is fixed in position, at its fore end, by a grooved jointing 22 in a cap 23 secured by nuts 24 to the hub 3a of the picking arm 3. The bar 21 is prevented from being longitudinally moved by means of screws 25 applying a cover 26 against cap 23. At its rear end, the bar is shaped to form projections 27 which are placed between abutting members 28 made integral with a flange 29, secured by bolts 30 at one end of a tubular casing 31, which is flared towards its other end in order to be attached to casing 9. This mounting is such that the projections 27 of the torsion bar 21 and the abutments 28 are provided and arranged in such a manner that the torsion bar comes into abutment only after having performed a certain angular movement. The tubular casing may comprise one or several struts fixed, for instance, at the rear of the casing. 20

Regarding the modification of the mounting, shown at Fig. 7, the torsion bar 21a is, at its fore end, fixed in position, in the same way as above described, on a cap 23a, but the height of said cap has been made longer in order to increase correspondingly the length of the bar. At its rear end, the flange 29a, having abutments 28a, is secured to the end of the tubular axle 19a which has been extended for that purpose. 30

In certain cases, the torsion bar 21a may be rigidly fixed, at its rear end, to the tubular shaft 19a in the same way as it is fixed at its fore end on the cap 23a which is made integral with the hub of the picking arm. 40

In the various embodiments described herebelow, the dimensions and the material of the tubular members 31 and 19 respectively forming the carrier of the rear end of the torsion bar 21, may be chosen in such a manner that said tubular member, under the action of said bar 21, acts too as a tubular torsion bar. 45

Regarding the embodiment of Fig. 8, the torsion bar 21b is combined with a second torsion bar 32b the rear end of which is coupled with the rear end of bar 21b by bevel wheels 33b and 34b mounted on respective grooves 35b and 36b formed on said bars. The other end of the bar 32b is fixed in position by a grooved jointing 37b in a carrier 38b formed integral with the tubular casing 31b. The bar 32b may occasionally be longer and fixed at the fore part of the casing 9b. The bevel wheels may be cut into the torsion bars. 50

In the embodiment of Figs. 9 and 10, the torsion bar 21c, having a great length, is fixed at its fore end on a part made integral with the picking arm, as above described with reference to Fig. 4. At its rear end, it comprises a rectangular head 38c the upper and lower parts of which, respectively shown at 38'a and 38'b, are in the shape of portions of cylinders. This head is mounted on a guiding bore 39c of a stationary carrier 40c. In that way, the bar 21c is tightly guided while being able to slightly go forward and backward according to the movements of the casing 9c. 38'c and 38''c are respectively the positions of the head 38c when the casing is in the extreme positions shown by the corresponding positions 17'c and 17''c of its cover. A fork 41c may be provided to guide the bar 21c at its middle portion. 65

When the casing 9c coming from its middle position 17c is oscillating rearwardly up to 17''c, the head 38c 70

moves up to 38''c and acts on the bar in such a manner that it is deflected along the line 21''c. In that way, the bar acts as a torsion bar and flexion bar.

The operation is the same when the casing, leaving 5 again its middle position 17c and oscillating forwardly up to 17'c, the head 38c moves up to 38'c and acts on the bar in such a manner that said bar is deflected along the line 21'c. When deflecting about the ends of its strokes, the bar stores up the kinetic energy of the casing and of the picking arm, when they are oscillating forwardly and rearwardly, and then gives said energy back at the beginning of the following oscillation.

It is possible to increase or decrease the deflection of the bar by directing differently the guiding bore 39c. It is also possible to suppress the deflection by making the guiding bore movable, for instance under the action of a cam. This cam would transfer the center 42c of the head 38c to the respective positions 42'c and 42''c, when the casing 9c would go from 17c to respectively 17'c and 17''c, the points 42'c, 42c and 42''c being on an arc of a circle described by taking as a centre the pivoting point 6c of the casing 9c. 20

It is obvious that many variations and modifications may be resorted to by those skilled in the art without departing from the scope of this invention as disclosed in the present specification and defined by the appended claims. 25

Thus, the torsion bar, instead of being made integral with the hub of the picking arm by means of the cap 23, may be fixed to an axle passing through the hub of the picking arm, the shaft about which the picking arm oscillates being provided with ports enabling the picking arm to be oscillated in spite of the axle. 30

The torsion bar may be made integral with the picking ram to operate as a shaft, for said picking arm, one or more bearings being then provided for carrying the bar. 35

The abutments 28 of the rear end of the torsion bar may have their position made adjustable, by screw or otherwise.

In the embodiments of Fig. 8, the bevel wheels may be changed for toothed sectors or any other suitable members transmitting the rotations of the bar 21b. On the other hand, instead of a single torsion bar such as 32b, it is possible to provide several such bars, symmetrically or not symmetrically, arranged with respect to the main bar 21b. 45

What I claim is:

1. In a shuttleless loom comprising a batten, an oscillating picking arm, and a sword carrying said batten; a lower shaft, a main casing rotatably mounted upon said lower shaft, a cross-piece connecting said casing with said sword, operating means located within said casing and operatively connected to said lower shaft and to said picking arm for oscillating said picking arm, said picking arm having a hub, a torsion bar attached at one end thereof to said hub, and retaining means carried by said loom and connected to the other end of said torsion bar, said means being adapted to prevent any rotational movement of said other end of said torsion bar. 50

2. The combination of claim 1, wherein said retaining means are constituted by a tubular casing surrounding said torsion bar and having one end thereof fixedly secured to said main casing and the other end thereof adjacent and secured to said other end of said torsion bar. 65

3. In a shuttleless loom comprising a batten, an oscillating picking arm, and a sword carrying said batten; a lower shaft, a casing rotatably mounted upon said lower shaft, a cross piece connecting said casing with said sword, a cam keyed upon said lower shaft and located within said casing, said cam having a helicoidal groove formed therein, a roller carried by said picking arm and located in said helicoidal groove, said picking arm having a hub, a tubular shaft carrying said hub, an elongated torsion bar extending through said tubular shaft, means firmly 70

connecting said hub and one end of said torsion bar, an independent stationary carrier having a movable guiding bore formed therein, and means adjusting the direction of said movable bore according to the position of said carrier, the other end of said torsion bar being longitudinally movable in said bore.

4. In a shuttleless loom comprising a batten, an oscillating picking arm, and a sword carrying said batten; a lower shaft, a casing rotatably mounted upon said lower shaft, a cross piece connecting said casing with said sword, a cam keyed upon said lower shaft and located within said casing, said cam having a helicoidal groove formed therein, a roller carried by said picking arm and located in said helicoidal groove, said picking arm having a hub, a tubular shaft carrying said hub, and a torsion bar combination comprising a torsion bar located in the center of said tubular shaft, and at least one auxiliary

torsion bar having one end connected with the first-mentioned torsion bar, one end of said torsion bar combination being firmly connected with said hub, the other end of said torsion bar combination being firmly connected with said tubular shaft.
